UNITED STATES PATENT OFFICE

LOUIS F. HAGEMANN, OF NIAGARA FALLS, NEW YORK, ASSIGNOR TO AMERICAN SALES BOOK COMPANY, LIMITED, OF TORONTO, ONTARIO, CANADA, A CORPORATION OF CANADA

AUTOGRAPHIC REGISTER

Application filed September 11, 1920, Serial No. 409,572. Renewed June 20, 1928.

This invention relates to autographic registers, and with respect to its more specific features to autographic registers adapted to utilize two or more superposed printed record strips or webs with manifolding accessories.

One of the objects of the invention is the provision of a practical autographic register of the character referred to, of simple construction, adapted to successively register the superposed printed forms of two or more strips or webs with each other and to permit rapid and easy threading and starting of the machine with the forms in registry.

Other objects will be in part obvious and in part pointed out hereinafter.

The invention accordingly consists in the features of construction, combinations of elements and arrangement of parts which will be exemplified in the construction herein-after set forth, and the scope of the application of which will be indicated in the following claims.

In the accompanying drawings forming part of this specification, and wherein similar reference characters refer to similar parts throughout the several views,

Figure 1 is a plan view of an autographic register embodying the invention;

Fig. 2 is a vertical central section of Fig. 1;

Fig. 3 is a detail of the feed end of the register, the cover plate being shown broken off and elevated; and

Fig. 4 is an end view of the feed mechanism, partly in section, for clearer disclosure.

Referring now more specifically to the drawings, the register embodies a light metallic framework providing end walls 1 and 2 and two side walls 3 forming a casing or a chamber for the reception of the webs or rolls of record strip, three of which rolls are illustrated at 4, 5, and 6. In the present embodiment each roll rests upon bottom flanges 7 fastened to the sides 3 and also upon inclined ways, or plates, 8 supported by the side plates 3. From each of the rolls 4, 5, and 6, the several webs are passed around guide rollers 9, 10 and 11, respectively, over a platen 13 and thence between the feed rolls of the machine, all as illustrated in Fig. 2. From

this construction it will be perceived that when the webs are pulled or fed to the left in Fig. 2, the rolls 4, 5 and 6 tend to be drawn up the inclines 8 and thereby exert a certain tension upon the respective webs tending to retract the webs. It is to be understood, however, that any other practical form of web tensioning means is within the purview of this invention.

The feeding of the webs is effected by a pair of rotatable elements 14 and 15, constituting a feed roller and cooperative member adapted to grip the webs. The numeral 12 indicates a shaft, journaled in the side walls of the frame, or casing, provided with a handle 13 for rotating the same and having two discs, or feed rolls, 14 which operate in conjunction with the cooperative member, or roller, 15 to grip and feed the webs lying therebetween. Each web has a series of similar forms printed thereon as indicated, for instance, by the lines 16, and between the successive forms each web has one or more apertures, in the present instance, two apertures 17, transversely in alignment with each other and longitudinally in alignment with the discs 14. A portion of the gripping surfaces or peripheral edges of the discs 14 are of a restricted width so as to enter the feed-arresting apertures 17 when the latter come between these discs and the roller 15 so that at that time the particular web is not effectively gripped by the feed rolls, and in consequence the feed of the web ceases notwithstanding continued rotation of the discs 14.

In the present embodiment the machine has a top, or cover 18, hinged to the sides 3 at 19, at the feed end of the frame, so that the cover may be turned on its hinge into the position illustrated in Fig. 3 thereby permitting access to the chamber and interior parts. The upper feed roller 15 has bearings or journals, 20 at each end which lie in slots 21 in the end walls 22 of a housing 23 at the front end of the cover, said housing being an arched chamber integral with the cover 18. The bottom walls of the slots 21 are formed by removable plates 24 held in place by screws. The journals 20 bear, at times, on the plates 24 and are spring-pressed downwardly by

springs 25 pressing against the followers 26. The proportion of parts is such that when the cover 18 is in the closed position, as illustrated in Fig. 2, for instance, the upper roller 15 is 5 spring pressed towards the discs 14, the journals 20 being lifted somewhat off the bearing plates 24. Thus there is a resilient gripping effect by the feed rolls on the webs.

In the present embodiment the peripheral 10 dimension, or circumference, of the discs 14 is slightly greater than the distance between successive sets of apertures 17 so that one rotation of these discs feeds the webs forwardly 15 an amount approximately equal to the distance between the successive sets of apertures whereupon the advance of the webs ceases and the rotation of the discs 14 is arrested. The numeral 27 indicates a stationary stop on the side of the frame of the machine, being a 20 pin bolted in position. The handle 13 is slideable on a sleeve 28 projecting from the crank arm 29 and has a pin 30 slideable therewith into and out of a path intersecting the stop 27. A spring 31 is employed to press the pin 25 30 in a path intersecting the stop 27.

The feed device is provided with means to start the feed of the paper webs after their 30 advance has been arrested by the apertures coming between the feed rolls. In the present embodiment the starting is effected by widening the discs 14 for a short portion of the periphery thereof. As illustrated each disc is in effect widened, or laterally enlarged at its 35 periphery by being provided with the laterally disposed curved plates 40 which may be cast integrally therewith or bolted thereto and are flush with the edges of the discs. These plates are disposed to contact the webs at the sides of the perforations 17.

40 One end of the roller 15 is provided with gear teeth 41 which mesh with teeth of a gear 42 rotating with the shaft 12 so that rotation of the two feed rollers is positively effected, one in conjunction with the other.

45 The numerals 43 indicate pins which are separate from the feed mechanism and are adapted to register the webs relative to each other and to the machine. These pins are fixed and are mounted upon the front end of 50 the machine in advance of the line of grip between the feed rolls and preferably are forwardly pointing, as seen in Fig. 2, so as to permit the webs to readily move thereover and to be disengaged therefrom upon an 55 advance movement of the webs. The pins 43 are transversely in alignment with each other and longitudinally in alignment with the apertures 17. They are placed at a readily accessible portion of the machine in front 60 of the feed mechanism.

The numeral 44 indicates the tearing bar which, in the present embodiment, is formed by the lower front edge of the housing 23. It will be observed that the tearing bar 44 65 moves with the cover 18 on the hinge or pivot

19, said cover being pivoted at the points through the instrumentality of the arms 45 extending from each side of the front end of the cover. The numeral 46 indicates a link pivoted to the cover at 47 and having a slot 48 engaging a pin 49 on the side of the frame. When the cover is turned up into the position illustrated in Fig. 3, the link 46 limits the angular movement of the cover and retains it in upright position. When the cover is lowered 75 to the position illustrated in Fig. 2 it may be locked down by any suitable means.

The numeral 50 indicates a receptacle for carbon paper sheets which are intended to extend laterally between the webs and the 80 free ends of the carbon paper sheets may be held by a bar 51 pivoted at 52 and lying close alongside the frame.

In operation, the rolls of web are placed in the machine as illustrated in Fig. 2, the cover, however, being up. The free end of each web is drawn forwardly over the platen 13' and one set of apertures 17 engaged with the pins 43, also the carbon sheets are disposed between the webs. In this wise the webs and the forms 90

thereon will be registered relative to each other, and free movement is permitted at this time because the feed rolls are not in contact with each other. The cover may now be lowered, whereupon the webs will be resiliently gripped between the feed rolls. Rotation of the feed rolls by turning handle 13 will advance the webs until the next successive set of apertures 17 arrives between the feed rolls, whereupon the advance movement of the webs 95 will cease and the webs will align themselves because the feed disks then penetrate the apertures without effectively gripping the webs. This engagement of the feed disks with the 100

apertures preferably occurs shortly prior to the arrest of rotation of the disks by the stop 27. The further rotation to bring the pin 30 in contact with the stop 27 brings the advance ends of the starting plates 40 into contact with the webs so that the webs will be gripped 105 between these plates and the upper feed roll 15, and held firmly while inscription and tearing off are effected. Likewise the plates 40 will then be in position to immediately start the feed of the webs upon further rotation of the handle 13. The numeral 55 indicates a pawl pivoted on the inner face of one of the plates 3 and adapted to engage a tooth 56 on a collar on the shaft 12 just before the pin 30 engages the stop 27. The pawl 55 cooperates with the pin 27 to resist the accidental operation of the feed rolls in either 110 direction.

115 It will be understood that should the distance between the successive sets of apertures 17, be greater than the peripheral length of the feed disks, as, for instance, twice as great, the feed disks may be turned twice to bring 120 up the next set of apertures to position between the feed rolls.

As before explained, the tendency for the webs to be retracted is augmented by the rolls 4, 5 and 6 being drawn up the inclines 8. Thus, these inclines may cooperate to exert a 5 rearwardly directed effort upon the webs or strips to move or adjust them rearwardly. When the narrow parts of the feed disks 14 enter the apertures 17, the grip of the feed is released in the webs, with the result that 10 the webs tend automatically to be retracted or drawn rearwardly. As the webs are now loose from the feed grip of the disks, they will automatically be adjusted into predetermined relation to each other, and it will be 15 perceived that this capability of relative adjustment pertains so long as the disks are in the apertures 17 and even though continued operation of the feed mechanism be effected. Soon, however, the enlarged or starter portions 20 40 of the disks 14 cooperate, in turn, to exert a grip on the strips and to continue the feed, this gripping continuing until another feed operation is to be started. Thus, after the arrest of feed due to the narrow peripheries of the disks 14 entering the apertures 25 17, these web-gripping, starting lugs 40 also cooperate as web-securing means, so as to secure the webs firmly in aligned writing position at the time of tear-off of the forwardly 30 fed inscribed web end sections. Also, the stop 27 cooperates with the pin 30 positively to arrest turning of the feed disks 14 when the strips or webs have become secured by the lugs 40 as described, and at a predetermined 35 point of disk rotation, so that the advance set of printed forms will have been aligned in writing position.

Thus by the above described construction are accomplished, among others, the objects 40 hereinbefore referred to.

As many changes could be made in the above construction and many apparently widely different embodiments of this invention could be made without departing from 45 the scope thereof, it is intended that all matter contained in the above description or shown in the accompanying drawings shall be interpreted as illustrative and not in a limiting sense.

It is also to be understood that the language 50 used in the following claims is intended to cover all of the generic and specific features of the invention herein described, and all statements of the scope of the invention 55 which, as a matter of language, might be said to fall therebetween.

Having described my invention, what I claim as new and desire to secure by Letters Patent is—

60 1. In a machine of the character described, in combination, a feed roller and cooperative member adapted to grip and feed a web, a portion of the periphery of said roller being of a width to enter apertures in the web and thereby cause cessation of feed, and fixed

pins separate from the feed roller adapted to engage apertures in the web to longitudinally register the web relative to the machine.

2. In a machine of the character described, in combination, a feed roller and cooperative member adapted to grip and feed a web, a portion of the periphery of said roller being of a width to enter apertures in the web and thereby cause cessation of feed, and fixed pins adapted to engage said apertures to register the web relative to the machine. 70 75

3. In a machine of the character described, in combination, a feed roller and cooperative member adapted to grip and feed a web, a portion of the periphery of said roller being of a width to enter apertures in the web and thereby cause cessation of feed, and forwardly pointing fixed pins adapted to engage said apertures to register the web relative to the machine. 80 85

4. In a machine of the character described, in combination, a feed roller and cooperative member adapted to grip and feed a web, a portion of the periphery of said roller being of a width to enter apertures in the web and thereby cause cessation of feed, and fixed pins separate from the feed roller adapted to engage apertures in the web to longitudinally register the web relative to the machine, said pins being in advance of the line of grip between said roller and said member. 90 95

5. In a machine of the character described, in combination, a feed roller and cooperative member adapted to grip and feed a web, a portion of the periphery of said roller being of a width to enter apertures in the web and thereby cause cessation of feed, and fixed pins adapted to engage said apertures to register the web relative to the machine, said pins being in advance of the line of grip between 100 105 said roller and said member.

6. In a machine of the character described, in combination, a feed roller and cooperative member adapted to grip and feed a web, a portion of the periphery of said roller being of a width to enter apertures in the web and thereby cause cessation of feed, pins separate from the feed roller adapted to engage apertures in the web to longitudinally register the web relative to the machine, said pins being in advance of the line of grip between 110 115 said roller and said member, and a web severing member in rear of said pins and ahead of said line.

7. In an autographic register, in combination, inclined ways for a plurality of web supply rolls, a feed roller and cooperative member adapted to grip and feed webs from said supply rolls and cause said rolls to move up said ways, and fixed pins adapted to engage apertures in said webs and thereby register predetermined portions of said webs with each other. 120 125

8. In a machine of the character described, in combination, a feed roller and cooperative member adapted to grip and feed a web, a 130

portion of the periphery of said roller being of a width to enter apertures in the web and thereby cause cessation of feed, fixed pins 5 separate from the feed roller adapted to engage apertures in the web to longitudinally register the web relative to the machine, and means movable with said feed roller to start the feed of the web.

9. In a machine of the character described, 10 in combination, means to register the forms of superposed strips of connected forms in sets of one form from each strip in writing position, including mechanism to advance the strips rendered ineffective to advance by feed 15 control form registry apertures in the strips positioned to stop the feed of each strip as a form thereon comes into writing position, and fixed means to initially position the strips with the first forms in registry and with the 20 form registry apertures in lateral alignment.

10. In a machine of the character described, 25 in combination, means to register the forms of superposed strips of connected forms in sets of one form from each strip in writing position, including mechanism to advance the strips rendered ineffective to advance by feed 30 control form registry apertures in the strips positioned to stop the feed of each strip as a form thereon comes into writing position, means to initially position the strips with the first forms in registry and with the form 35 registry apertures in lateral alignment, including fixed pins spaced laterally to correspond with the spacing of the apertures and arranged beyond the advancing mechanism.

11. In a machine of the character described, 40 in combination, a feed roller and cooperative member adapted to grip and feed a web having successive apertures, a handle and operative connections for rotating said roller, a portion of the periphery of said roller being of a width to enter an aperture in the web and thereby cause cessation of feed, other 45 portions of said periphery being adapted to overlap the lateral edge of said aperture, means adapted to arrest the rotation of said roller in either direction when the web is gripped by the advance end of said overlapping portion, said overlapping portion of 50 the periphery being disposed closely in rear of said aperture when the other portion is in said aperture, and fixed pins in advance of the line of grip between said roller and said member and in longitudinal alignment with 55 the apertures.

12. In a machine of the character described, 60 in combination, a feed roller and co-operative member adapted to grip and feed a web having successive apertures, a handle and operative connections for rotating said roller, a portion of the periphery of said roller being of a width to enter an aperture in the web and thereby cause cessation of feed, other 65 portions of said periphery being adapted to overlap the lateral edge of said aperture,

means adapted to prevent the rotation of said roller in either direction when the web is gripped by the advance end of said overlapping portion, fixed pins in advance of the line of grip between said roller and said member and in longitudinal alignment with the apertures, a cover member hinged forwardly of the feed roller and supporting said co-operative member, and a tearing bar 70 for the web integral with the cover and intermediate the feed roller and said pins. 75

13. An autographic register including a casing to receive record strips formed with feed-arresting apertures, means mounted by said casing and engaging superposed strips 80 to move the same with respect to said casing and cooperating with said apertures to arrest the feed of said strips and means beyond said last named means to extend through the apertures of said strips and establish the same in 85 proper registry.

14. An autographic register including a casing to receive record strips formed with feed-arresting apertures, means mounted by 90 the casing and engaging superposed record strips to feed the same and cooperating with said apertures to arrest such feeding and means fixed with respect to said casing and disposed beyond said strip-feeding means to extend through the strip apertures and establish the strips in proper initial relationship. 95

15. An autographic register including in combination a casing to receive a plurality of superposed record strips having feed-arresting 100 apertures, means acting upon said strips to draw the same rearwardly, a pair of rotatable elements mounted by said casing and cooperating with said record strips to feed the same forwardly, one of said elements comprising a disk having a peripheral edge, restricted to enter the feed-arresting apertures of the strip, the circumference of said disk being in excess of the distance between successive feed-arresting apertures in said strip, 105 an enlarged portion forming a part of the disk periphery, means for turning said disk whereby to cause the record strips to be fed forwardly to a point at which the periphery of the disk moves into the feed-arresting apertures of said strips and the latter tend to 110 move rearwardly and into predetermined relationship with respect to each other, said enlarged portion of the disk subsequently 115 cooperating with said strips to exert a grip upon them and thereby to continue the feeding and prevent relative movement thereof after they have established proper relative positions, and means for thereupon preventing a further turning of said disk during 120 continuance of said grip upon said strips. 125

16. An autographic register including means for feeding a plurality of superposed record strips, means acting during the continuing operation of said feeding means to arrest the feeding of said strips, means for 130

automatically adjusting said strips to assume predetermined relative positions, gripping means for subsequently exerting gripping action upon said strips to secure them against 5 relative movement, and means for thereupon stopping the actuation of said feeding means during continuance of said gripping action upon said strips.

17. An autographic register including a 10 casing to receive a plurality of strips formed with feed-arresting apertures, means mounted by said casing and engaging the strips to feed the same and cooperating with said apertures to arrest such feed and a pin mounted 15 by said casing at a point beyond said last named means and in line with the apertures of said strips, said strips being disposable with the pin extending through the apertures thereof to establish the initial position 20 of said strips.

18. An autographic register including a casing to receive record strips having pairs of feed-arresting apertures, means mounted by the casing and engaging the strips for feed- 25 ing the same, said feeding means being disposed with respect to the pairs of strip apertures to arrest the feed of said strips and a pair of pins fixed to said casing and arranged beyond said feeding means and in line with 30 the apertures of said strips to extend therethrough and establish the initial relationship of said strips with respect to each other.

19. A machine of the character described including, in combination, feeding mechanism 35 including a rotary feed disk having a feeding grip with one or a plurality of relatively superposed webs or record strips in alignment with feed controlling apertures therein, so that the feeding grip on the web is 40 released and feed arrested during continued disk rotation by registry of said apertures with the grip of the disk, web securing-means actuated by said feeding mechanism and including a gripping device exerting gripping 45 action upon said webs and securing them against movement subsequently to the said release of said feeding grip, and means for thereupon stopping actuation of said feeding mechanism during continued gripping action 50 of the gripping device of said web-securing means.

20. A machine of the character described including, in combination, means for feeding a plurality of superposed record strips, means 55 acting during the continuing operation of said feeding means to arrest the feeding of said strips, strip-securing means actuated by said feeding means and including a gripping device exerting a gripping action upon said 60 strips and securing them against movement subsequently to the arrest of the strip feed, and a stop device for thereupon stopping the actuation of said feeding means during continued gripping action of the gripping device 65 of said strip-securing means.

21. An autographic register including, in combination, means including a strip-gripping, rotary feed disk for feeding one or a plurality of relatively superposed record strips, means acting during the continuing 70 rotary operation of said feed disk, to arrest the feeding of said strips and to release them, for adjustment, from the feeding grip of the disk, strip-adjusting means exerting a rearward effort upon the strips when thus released 75 so as to adjust them rearwardly, said disk including strip-securing, gripping means exerting gripping action upon said strips after said adjustment thereof to secure them in adjusted position, and means for thereupon 80 checking the actuation of said feed disk during continuance of said securing gripping action upon said strips.

22. An autographic register including, in combination, means including a strip-gripping, rotary feed disk for feeding one or a plurality of relatively superposed record strips, means, acting during the continuing rotary operation of said feed disk, to arrest the feeding of said strips and to release them, 85 for adjustment, from the feeding grip of the disk, strip-adjusting means exerting a rearward effort upon the strips when thus released so as to adjust them rearwardly, a strip-securing device operatively actuated by said feed- 90 ing means to secure the strips in adjusted position after said adjustment thereof and means for thereupon checking the actuation of said feed disk during continuance of the securing action of said strip-securing device. 95

In testimony whereof I affix my signature.
LOUIS F. HAGEMANN.
